UNITED STATES PATENT OFFICE

MILTON H. SHOENBERG AND LESTER SCHON, OF SAN FRANCISCO, CALIFORNIA; SAID SCHON ASSIGNOR TO SAID SHOENBERG

CIRCUIT INTERRUPTER

Application filed August 13, 1925. Serial No. 49,976.

This invention relates to a circuit interrupter and has for its object the provision of an improved device of this character which is of simple and rugged construction and which may be used over a wider range of power than has heretofore been possible with devices of this character. More particularly, our invention relates to a circuit interrupter especially adapted for interrupting the circuit of electric lamps, where it is desired quickly to flash the same intermittently, and is of the thermostatically controlled type. Our invention is in the nature of an improvement over the socket interrupter shown in United States Letters Patent No. 1,400,914, issued to Milton H. Shoenberg on December 20, 1921, and particularly of the device shown and claimed in our Patent No. 1,602,088, granted October 5, 1926, of which this application is a continuation in part. In each of the foregoing inventions, an electric heating coil was employed which was in circuit with contacts normally closed carried by the thermostatic element, and the circuit was interrupted by the heating of said element. In these forms of devices, the range of use was more or less limited by the heating coil, since a coil designed for a lamp of high wattage would have a resistance too great for a lamp of fewer watts, and on the other hand, a coil designed for the lower watt lamp would be burned out with the larger lamps. We have found it possible to use an interrupter embodying our present invention over a range of from 2 to 250 watts.

It is therefore an object of this invention to provide a circuit interrupter that obviates the difficulties above described.

It is a further object of this invention to construct a novel device which may be removably positioned within a lamp socket or receptacle for recurrently varying the current supplied by the socket.

It is another object of our invention to greatly simplify upon the mechanical structure of devices which are shown in our Patent No. 1,602,088 to which reference has previously been made.

Further objects of the invention will appear from the following description in which

we have set forth the preferred embodiment of our invention. It is to be understood that the appended claims are to be accorded a range of equivalents consistent with the state of the prior art.

Referring to the drawings:

Figure 1 is a top view of an interrupter embodying our invention.

Fig. 2 is a sectional view taken on the line 2—2 of Fig. 1.

Fig. 3 is an enlarged view of the thermostatic unit.

Fig. 4 is a sectional view taken on the line 4—4 of Fig. 3.

Fig. 5 is a view partly in section, and partly in elevation illustrating our interrupter in operative position for flashing intermittently an incandescent electric lamp of the usual type; and

Fig. 6 is a view partly in section and partly in elevation illustrating an incandescent lamp provided with an interrupter embodying our invention.

In the invention herein disclosed, instead of utilizing a body comprising a plurality of parts, we utilize a body 1, which is preferably formed of a single piece of insulating material. This body is relatively flat or disc shaped and is sufficiently small in diameter

so as to readily enter a standard Edison type socket or lamp receptacle such as shown in Fig. 5. Formed within the body 1 and preferably offset from the center of the same, there is a recess 3 forming an opening in the body, and serving to accommodate a thermostatic unit or circuit interrupter element 2.

The body is also preferably provided with two openings 4 and 5 to receive eyelets 6 and 7 for securing contacts 8 and 9 to the body 1. As best shown in Fig. 2, the contacts 8 and 9 are secured to opposite sides of the body 1, and are bent outwardly at their free ends from the faces of the body 1, so as to form resilient or spring contacts, whereby good contact will be made between the same and the lamp socket and lamp. Preferably the free ends of the contacts 8 and 9 are enlarged

in the form of small discs 10 and 11 respectively which are positioned centrally with respect to the body 1.

The thermostatic unit 2 comprises two thermostatic elements 12 and 13 each of which is in the form of two strips 14 and 15 of metal fixed together, having different coefficients of expansion, preferably steel and brass respectively, the outside strip 15 in each case being of brass and the strips 14 facing each other being of steel, whereby expansion will cause the elements 12 and 13 to move toward each other. The elements 12 and 13 are separated at one of their ends by a high resistance block 16, preferably graphite, the resistance of which is preferably at least three times as great as that of the smallest lamp with which the interrupter is to be used, and the elements 12 and 13 are secured to the block 16 in any suitable manner, preferably by means of a silk thread 17 wound around the same as best shown in Fig. 3. The opposite ends of elements 12 and 13 are provided with contacts 18 and 19 which normally are separated and engage each other to close the electric circuit of the element to be controlled. The elements 12 and 13 are respectively electrically connected with the contacts 8 and 9 by suitable conductors 20 and 21. As shown in Fig. 1, the thermostatic unit 2 is placed in the opening 3 of the body 1 and the contacts 8 and 9 are secured to said body on opposite sides thereof. The assembled parts are placed in a cup-shaped container 22 which is closed by a similar container 23 which telescopes with the container 22 so as to form a closed container for the parts. The parts 22 and 23 are each provided with a cut or split 24 so that the contact ends 10 and 11 may project through the same respectively so as to be on the outside of the completed unit. The container parts 22 and 23 are made of suitable insulating material, and in the drawings such material is shown as transparent. From the foregoing detailed description of a construction embodying my invention, the operation of the same will be readily understood from a brief description thereof. When the complete unit, designated 25, is placed in a lamp socket 26, as shown in Fig. 5, one of the contacts 10, 11, makes contact with the contact 27 in the socket 26 and the other of said contacts engages the contact 28 of a lamp 29 screwed into the socket. Due to the resilient character of the contacts 10 and 11, a close contact with the socket contact 27 and lamp contact 28 is secured. When the lamp circuit is closed, the same is interrupted rapidly by the unit 25 so as to cause the lamp to flash intermittently. As above stated the contacts 18 and 19 carried by the thermostatic elements 12 and 13 are normally separated; thus when the lamp circuit is closed, the current passes from one of the contacts 10 or 11, which for purposes of illustration we may assume to be 10, through conductor 20, carbon block 16 and conductor 21 to the other contact 11. Due to the high resistance of the block 16, very little current passes to the lamp. As the current continues to flow through the block 16, the same is heated, thereby actuating thermostatic elements 12 and 13, causing the contacts 18 and 19 to engage and short-circuit the block 16. The current then flows through the lamp 29 from the socket contact 27, contact 10, conductor 20, element 12, contacts 18 and 19, element 13, conductor 21, contact 11 and lamp contact 28, and through the lamp to the opposite side of the circuit. The block 16 now being short-circuited, the same cools whereupon the lamp circuit is opened between contacts 18 and 19, and the excess current which momentarily accumulates when the circuit is interrupted, is absorbed by the resistance block 16, thereby reducing the sparking between the contacts 18 and 19 to a minimum. It of course is understood that the parts described are very sensitive and that operations described take place with rapid sequence.

In Fig. 6 we have shown our interrupter element embodied in an electric lamp and integral therewith. In this case the lamp base 30 is provided with a recess 31 to receive a thermostatic unit 2 similar to that shown in Fig. 1, and one of its conductors, for example 20, is electrically connected with the lamp filament 32 and the other of its conductors 21, is electrically connected with the lamp base contact 33. The operation in this case of course is similar to that above described in connection with Fig. 5.

It is obvious from the above description that we have provided a device of great simplicity which may be efficiently used in signals or other devices for flashing lamps. It is to be distinguished from adapters or other such devices in that our device is inserted within a lamp socket so that the lamp base or plug connector may be engaged with threads of the socket.

We claim:

1. In a circuit interrupter, two thermostatic elements adapted to move toward each other when heated, a single flat resistance element interposed between the same and in electrical contact therewith for heating said thermostatic elements, means for securing said thermostatic elements to said resistance element, and contacts normally separated carried by said thermostatic elements adapted to short circuit said resistance element when said thermostatic elements are heated.
2. A device of the class described comprising a disc of insulating material formed with an opening, resilient contacts on opposite sides of said disc, a thermostatic unit within said opening comprising a resistance element electrically connected in series with said contacts, a thermostatic element connected with each contact adapted to be heated by said re-

sistance element, a contact carried by each thermostatic element normally separated and adapted to engage and short circuit said resistance element when said thermostatic elements are heated.

said element serving to repeatedly vary current supplied to the socket.

In testimony whereof, we have hereunto set our hands.

MILTON H. SHOENBERG. 70
LESTER SCHON.

5 3. A device of the class described comprising a disc of insulating material formed with an opening, resilient contacts on opposite sides of said disc, a thermostatic unit within 10 said opening comprising a resistance element electrically connected in series with said contacts, a thermostatic element connected with each contact adapted to be heated by said resistance element, a contact carried by each 15 thermostatic element normally separated and adapted to engage and short circuit said resistance element when said thermostatic elements are heated and a casing for said disc having slots through which said resilient contacts project.

20 4. A device of the class described adapted to be removably positioned within a lamp socket or receptacle comprising a relatively flat wafer or disc having an opening there- 25 through, contacts positioned on opposite faces of said disc, an interrupter element positioned within the recess for recurrently varying current supplied by socket, and an insulated cover for the disc, to enclose the ends 30 of said opening.

5 5. A device of the class described adapted to be removably positioned within a lamp socket or receptacle comprising a relatively flat wafer or disc having an opening there- 35 through offset from the center of the disc, contacts positioned on opposite faces of said disc, an interrupter element positioned within the recess for recurrently varying current supplied by the socket, and an insulated cover 40 for the disc serving to close the ends of said opening, the cover comprising interfitting sections.

6 6. A device of the class described adapted to be removably positioned within a lamp 45 socket or receptacle comprising a relatively flat wafer or disc made substantially entirely of insulating material, contacts positioned on opposite faces of said disc, an interrupter element positioned within the disc for recur- 50 rently varying current supplied by the socket, and a cover of insulating material for the disc, said cover being apertured to permit external electrical connection with said contacts and serving to close said recess.

7 7. A device of the class described adapted to be removably positioned within a lamp socket comprising a body in the form of a single relatively flat member of insulating 55 material having a recess, an interrupter element disposed within the recess, and terminal contacts disposed upon opposite faces of the body, said contacts being insulated from direct electrical contact with each other by the insulating material of the member,
